MIT BESCHRÄNKTER HAFTUNG, OF COLOGNE-NIPPES, GERMANY.

INSULATOR.

1,031,453.

Specification of Letters Patent. Patented July 2, 1912.

Application filed September 27, 1910. Serial No. 584,009.

To all whom it may concern:

Be it known that we, HEINRICH LANGE and FRANZ DRUCKENMÜLLER, both subjects of the King of Prussia, and residents, respectively, of Kiel and Cologne-Nippes, Prussia, Germany, have invented a new and Improved Insulator, of which the following is a full, clear, and exact description.

This invention relates to insulators for high tension and other electric conductors, and has reference more particularly to an insulator comprising a core and an insulating body having said core embedded therein, said core constituting a reinforcement for said body, means for securing the conductors to the body, and a jacket upon said body, consisting of insulating material, the resistance of which is not affected by the action of light, air, salt water, smoke, etc.

The object of the invention is to provide a simple and inexpensive insulator which can be used in connection with high-tension conductors of over-head electric systems for wireless telegraphy and telephony, as well as with the supporting tackle used with the masts of wireless telegraph systems, which possesses great strength, is of high resistive power, presents a large surface, which is of comparatively small circumference, and of light weight, and which can be inexpensively produced.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a longitudinal section of an embodiment of our invention. Fig. 2 is a similar view showing a modified form of the insulator. Fig. 3 is a similar view showing a further modified form of the insulator. Fig. 4 is a longitudinal section of another modified form of the invention; and Fig. 5 is a transverse section of the form shown in Fig. 4.

Before proceeding to a more detailed explanation of our invention, it should be clearly understood that while the insulator is particularly useful in connection with wireless apparatus, it can also be advan-

tageously employed for other purposes, in which electric insulators of considerable strength, light weight, and high resistive power are desired.

Certain of the details of construction, shown for example herewith, form no part of the invention, and can be varied in accordance with individual preference and special conditions, without departing from the underlying spirit of the invention.

Referring more particularly to the drawings, the form of the invention shown in Fig. 1 has a core 10 fashioned either from conducting or non-conducting material, such as bronze, steel, or the like, or wood fibers, gut, etc. The core is of elongated form and has enlargements 11 at the ends. The body of the insulator, 12, has the core embedded therein, and is of elongated form with enlarged ends 13, which receive the corresponding parts 11 of the core. Sockets 14 receive the enlarged ends of the body and have inwardly disposed flanges 15 engaging at the enlargements 13. The sockets have associated therewith, integrally or otherwise, eyes 16 to which the conductors or other members carried by the insulator are secured. The jacket 17 encompasses the body of the insulator between the ends thereof, and is of suitable length to extend nearly to the extremities of the insulator. It is fashioned from any suitable material, the resistance of which is not affected by light, air, sea water, etc., consisting for example, of amber, or glazed porcelain. The non-conducting body 12 may be fashioned from any material of high resistivity, for example, from hard rubber or the like.

In the form of the device shown in Fig. 2, we employ two cores 18, spaced apart, and having serrated, enlarged ends 19. The body 20 in which the cores are embedded, is similar to the body 12. The remaining elements of this form, consisting respectively of the sockets 19 and the jacket 21, correspond to the like elements in the previously described modification.

The above types of the insulator are intended for lighter work. In Fig. 3 I have illustrated however, a form of the device which is adapted for very heavy work, the loads which it is capable of supporting being as high as one hundred thousand pounds. The reinforcing core 22 is of substantial

form and has near the ends openings 23. The body 24 of the insulator is fashioned from material of high resistivity, and encompasses the core and also lines the openings. The jacket 25 is similar to the jacket 21 or the jacket 17. In the openings 22 are bearing members 26, which support the conductors or cables with which the insulator is used.

- 10 In Figs. 4 and 5 we have illustrated a further modified form of the insulator similar to the form mentioned, but having the core 27 of cross-shaped section, intermediate the ends, for purposes of lightness. The 15 body 28 encompasses the core, and the remaining elements of the insulator are similar to those shown in Fig. 3.

Having thus described our invention, we claim as new, and desire to secure by Letters Patent:

1. An insulator, comprising a bar-like core, an insulating body wholly encompassing the core, a single elongated tube of insulating material and surrounding the body, 25 said tube terminating short of the ends of

the body, and conductor securing means at the ends of the insulator.

2. An insulator, comprising a bar-like core having transverse openings in its ends, an insulating body wholly encompassing the 30 core and lining the opening thereof, and an insulating jacket surrounding the body.

3. An insulator comprising a bar-like core, cross-shaped intermediate of its ends and having a transverse opening in each 35 end, an insulating body wholly encompassing the core and lining the openings thereof, and an insulating jacket surrounding the body.

In testimony that we claim the foregoing 40 as our invention, we have signed our names, in presence of two subscribing witnesses.

HEINRICH LANGE.
